INDEXING MEANS

Wendell L. Carlson, Haddonfield, N. J., assignor to
 Radio Corporation of America, a corporation of
 Delaware

Application August 14, 1940, Serial No. 352,509

8 Claims. (Cl. 74—10)

This invention relates to methods and means for achieving the rapid and accurate setting of a dial, such, for example, as the tuning dial of a radio set.

The prior art is replete with indexing mechanisms comprising a pawl and a main or auxiliary dial plate provided with detents or notches which are individual to the more frequently dialed settings, and which are selectively engaged by the pawl when the desired setting is achieved. Thus, the dial may be moved rapidly over the pawl to the approximate setting desired whereupon the pawl engages the detent individual to that setting and the operator is advised by his sense of touch that an exact setting has been achieved.

The principal objection to the indexing mechanisms of the prior art is that they either require at least partial disassembly of the radio or other apparatus during the setting-up process or are otherwise so complicated in their adjustment as to inhibit their use by an unskilled operator. As to the above, see by way of example, "Wireless World" (British) February 9, 1927, page 162; see also U. S. Patent 1,964,449 to W. L. Carlson.

Accordingly, the principal object of the present invention is to provide a simple, inexpensive and trouble-free indexing mechanism for radio tuners and the like and one which lends itself readily to accurate permanent adjustment by an unskilled operator without disassembly of any part thereof and without danger of impairing previous set-ups.

The foregoing and other objects are achieved in accordance with the invention by the provision of a dial plate constituted of a relatively soft metal, such, for example, as copper, brass or the like, and by making the detents or notches individual to the several settings therein as by a punch, thrust, or other force applied to the said soft metal plate, preferably from the front of the set, without removing it from the tuning control or other shaft upon which it is mounted. In accordance with the invention, the instrument by which the dial plate is notched may comprise the pawl of the indexing mechanism.

Other objects and advantages together with certain details of construction will be apparent and the invention itself will be best understood by reference to the following specification and to the accompanying drawings, wherein:

Figure 1 is a front elevational view of a radio tuning unit with the control panel broken away

to reveal an indexing device constructed in accordance with the principle of the invention,

Figure 2 is a fragmentary plan view of the device of Fig. 1 showing the detent forming element in operation,

Figure 3 is a sectional view taken on the line 3—3 of Fig. 1,

Figure 4 is a front plan view of a radio tuner showing another embodiment of the invention,

Figure 5 is a sectional view taken on the line 5—5 of Fig. 4, and

Figure 6 is a schematic view showing the invention applied to a so-called permeability tuning system.

15 In the embodiment of the invention shown in Figs. 1, 2 and 3, 1 designates the front surface and 3 a shelf or base comprising the chassis of a radio set having a control panel 5. A tuning condenser 7, mounted on the base 3, has a main shaft 9 which is susceptible of 180° rotation under the control of a knob 11 which is affixed to its outer end adjacent the front of the control panel 5. Fixed to the main tuning shaft 9 as by means of a collar 13 is a disc 15 at least the lower half of which is constituted, in accordance with the invention, of copper, brass or other relatively soft and easily deformable material.

30 Immovably mounted in front of the disc or plate 15, as in an escutcheon 17 on the control panel 5, is a dial face 19 which may be provided with radially extending slots 21 or other means in which station markings 23, or other indicia may be inserted. The scale markings 23 may be

35 read in conjunction with a pointer 25 on the control knob 11. Alternatively, the dial face 19 may be fixed on the disc 15 for rotation therewith, in which case a fixed pointer (not shown) may be provided on the control panel 5 or on the escutcheon 17. If desired, the lower half of the dial face 19 may be calibrated in terms of frequency or wave length.

40 A weighted spring-actuated wedge or V-shape element 27 is mounted adjacent the periphery of the soft metal disc 15 for forming therein the notches or detents 29 which are individual to the more frequently dialed stations. The wedge shaped element 27 is formed of a relatively harder metal than the disc 15 and is carried on, or forms part of, a flat spring 31 which is supported at one end on a block 33 on the front surface 1 of the chassis or base upon which the tuning element 7 is mounted.

45 The wedge-shaped detent-forming element 27 lies adjacent the free end of the spring 31. This

free end of the spring 31 carries on its under side a weight 35 and an arm or cam follower 37 which, when pressed downwardly as by means of a cam 39 and suddenly released, imparts a force to the wedge shaped element 27 of an intensity sufficient to form a notch or detent 29 in the soft metal disc 15. The cam 39 for actuating the weighted detent-forming element 27 preferably has a gradual rise from the point A to the point B and a sudden dwell or drop from the point B to the point A. Thus, as it is rotated counter-clockwise in contact with the cam follower 37, the weighted spring 31 is drawn away from the periphery of the disc 15 and suddenly released with a force sufficient to drive the wedge shaped element 27 into the relatively softer metal of which the index plate or disc 15 is constituted.

Since the notches or detents 29 are formed in situ, that is, without removing the disc 15 from the tuning control shaft 9, or otherwise disassembling the set, it is apparent that in setting up or indexing the unit, it is merely necessary to rotate the tuning control shaft 9 and the disc 15 thereon to that angular position whereat the station to be indexed is tuned in and, with the disc in that position, to actuate the detent forming element 27 by means of the knob 41 on the shaft 43 for the cam 39. Since the detent-forming element 27 is normally biased by the spring 31 against the periphery of the disc 15, the said element 27 serves as a pawl for the detents in said disc. Thus, when the tuning shaft 9 and the disc 15 thereon are later rotated to tune in a desired station, the pawl moves in and out of the detents individual to the other stations in the set up until the approximate setting of the desired station is reached, whereupon the V-shaped element or pawl 27 engages the detent individual to that station and the operator is advised by his sense of touch that the exact setting for that station has been achieved.

Referring to Fig. 3, the shaft 43 to which the knob 41, and cam 39 are attached may be mounted in a bushing 45 for both rotational and axial movement. The bushing 45 has a spirally tapered end, with a drop or detent C in its taper, and the shaft 43 is provided with a pin 47 which rides on this tapered end until it abuts the stop C, hence in order to project the cam follower 37 (see Fig. 2) over the drop B—A of the cam 39, for indexing purposes, it is necessary to push the knob 41 inwardly against the force of a biasing spring 49 prior to rotating it. As shown in Fig. 2 when it is desired to tune the set to an unindexed station the knob 41 may be partly rotated, say 180°, to withdraw the wedge shaped element 27 away from the indexing disc 15.

In the embodiment of the invention shown in Figs. 4 and 5, the indexing disc, which is here designated 55 is immovably fixed to a supporting plate 57 at the rear of the control panel 59. The indexing or disc plate 55 is provided with an outwardly turned soft-metal rim *r* in which the notches or detents 61 individual to the stations are formed by means of a wedge-shaped element 63 carried on a spring 65 which is mounted on the main tuning shaft 67 adjacent the rear surface of the tuning control knob 69. The wedge-shaped detent forming element 63 is accessible from the front of the set through an orifice 71 which is provided for the purpose in the knob 69. Thus, in order to set up a station it is merely necessary to insert a punch (not shown) into the orifice, and with the lead-

ing end of the punch in contact with the outer surface of the wedge-shaped element 63 to deal the punch a thrust or blow of an intensity sufficient to deform the soft metal of which the rim *r* of the disc 55 is constituted.

As above indicated, and as in the previously described embodiment of the invention, the wedge-shaped detent forming element 63 is spring mounted and, during subsequent tuning operations comprises a pawl for the detents in the indexing disc or plate 55.

It is not to be inferred from the foregoing description that the invention is limited to installations wherein the indexing plate is employed in conjunction with a conventional condenser type of tuner, as it may readily be adapted to tuners of other types. Thus, referring to Fig. 6, the invention is shown as applied to a cord driven permeability type tuning system wherein movement of a magnetic core 75 within a coil 77 provides the requisite changes in the electrical circuits essential to tuning. In this embodiment of the invention, the indexing mechanism is similar to that described in connection with the device of Figs. 1-3 with the exception that the indexing plate 79 is mounted on a stub shaft 81 (instead of on the main tuning shaft) and is provided with a pulley 83 for a cord drive comprising a driving cord 85, pulleys 87, 89 and a second cord 91 whose ends are connected to the opposite terminals of the magnetic core 75.

Other modifications of the invention will suggest themselves to those skilled in the art. It is to be understood therefore that the foregoing description of certain presently preferred embodiments of the invention is to be interpreted as illustrative and not in a limiting sense except as required by the prior art and by the spirit of the appended claims.

40. What is claimed is:

1. In combination, an instrument capable of various settings and comprising an indexing element constituted of an easily deformed material, and means mounted in operative relation 45 with respect to said indexing element for generating and applying a deforming force thereto at points corresponding to selected ones of said settings.

2. The invention as set forth in claim 1 where- 50 in the means for applying said deforming force to said indexing element comprises a spring-actuated pawl.

3. In combination, radio apparatus having a tuning control shaft, an indexing element mounted 55 in operative relation with respect to said control shaft, and a pawl for said indexing element mounted adjacent said element, of means mounted in operative relation with respect to said indexing element for generating and applying a 60 force to said indexing element of an intensity sufficient to form a detent for said pawl in said element at a point corresponding to the setting of the station to be tuned.

4. The invention as set forth in claim 3 and 65 wherein said detent forming force is applied to said indexing element through said pawl.

5. In combination, radio apparatus comprising a control panel, a tuning control element mounted adjacent the front of said panel, a tuning control shaft controlled by said element, an indexing element mounted in operative relation with respect to said control shaft, and a pawl for said indexing element, of means accessible from the front of said control panel for forming a detent for said pawl in said indexing 75

element at a point corresponding to the setting of a station to be tuned.

6. The invention set forth in claim 5 and wherein said tuning control element comprises an apertured knob and said detent-forming means is accessible through said aperture.

7. In combination, an instrument capable of various settings and comprising an indexing element having a surface constituted of an easily deformed material, a pawl mounted adjacent 10 said indexing element and through which a deforming force may be applied to said surface at points corresponding to selected ones of said settings, means formally biasing said pawl into contact with said surface, and means for moving 15 said pawl against the force of its bias out of

contact with said surface of said indexing element.

8. In combination, an instrument capable of various settings and comprising an indexing element 5 constituted of an easily deformed material, a driven means mounted in operative relation with said indexing element for applying a deforming force thereto at points corresponding to selected ones of said settings, and actuating means for said driven means comprising a shaft mounted to permit of both rotary and axial movement and having an actuating element fixed thereon and movable into and out of engagement with said driven means upon axial movement of said shaft.

WENDELL L. CARLSON.
